Filed Aug. 14, 1962, Ser. No. 71,281

Term of patent 14 years

(Cl. D34—5)

FIG. 1.

FIG. 2.

The back of the game board is plain, and the side opposite to that disclosed in the drawing has substantially the same appearance as the side disclosed.

The dominant feature of the design resides in the portions of FIGS. 1 and 2 shown in full lines.

We claim:

The ornamental design for a game board, as shown and described.
